(57) **CLAIM**

The ornamental design for a hairsetter, as shown and described.

DESCRIPTION

FIG. 1 is a top perspective view of a hairsetter our new design with the electrical cord and top access area illustrated in broken lines;

FIG. 2 is a bottom perspective view thereof;

FIG. 3 is a top plan view thereof;

FIG. 4 is a bottom plan view thereof;

FIG. 5 is a left elevational view thereof;

FIG. 6 is a right elevational thereof;

FIG. 7 is a front elevational view thereof; and,

FIG. 8 is a back elevational view thereof.

The broken lines in FIGS. 1 through 8 illustrate a top access area and part of an electrical cord. The broken lines and the areas with the broken lines form no part of the claimed design.

1 Claim, 8 Drawing Sheets
